UNITED STATES PATENT OFFICE

121,460

DESIGN FOR A COMBINATION CALENDAR DESK PAD UNIT

William B. Petzold, Pittsfield, Mass., assignor to
General Electric Company, a corporation of
New York

Application March 26, 1940, Serial No. 91,249

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Combination Calendar Desk Pad Unit, of which the following is a specification, reference being had to the accompanying drawing forming a part thereof.

In said drawing:

Figure 1 is a front perspective view of a combination calendar desk pad unit showing my new design.

Figure 2 is a view in perspective showing the combination calendar desk pad unit in open position.

Figure 3 is a rear view of the combination calendar desk pad unit.

The printed matter shown in Figure 2 of the drawing is merely representative in character.

I claim:

The ornamental design for a combination calendar desk pad unit, as shown and described.

WILLIAM B. PETZOLD.
